UNITED STATES PATENT OFFICE.

FREDERICK L. FULDAUER, OF CLEVELAND, OHIO, ASSIGNOR TO AMERICAN STOVE COMPANY, OF ST. LOUIS, MISSOURI, A CORPORATION OF NEW JERSEY.

HYDROCARBON BURNER.

Application filed June 8, 1926. Serial No. 114,478.

This invention relates to improvements in hydrocarbon burners and the intention is that gasoline is to be used as a fuel, although other types of hydrocarbon can be utilized.

In carrying out the present improvement I utilize what may be termed as a main burner that is provided with a generator for vaporizing the hydrocarbon, and one or more burners communicating with the main burner housing to receive their supply of vapor from the said housing.

The primary object of this improvement is to so construct the main burner that the main burner can be cut off at will and at the same time the main burner housing and generator will furnish vapor for supplying the additional burner or burners.

A further object of the improved invention is to provide a main burner that is located outside of the oven and an oven burner located within or below the oven, and at the same time the main burner may be cut off at will and the generator still supply vapor to the main burner housing that will flow to the oven burner.

A further object of the invention is to provide the main burner housing at or near its top, with a disk located slightly below its top, and place a burner cap above the said disk and provide the said disk with a valved opening operative from the outside of the burner whereby the valve may be opened for supplying vapor or fuel to the burner cap or the valve closed and the vapor flow from the chamber in the lower part of the housing to either the oven burner or another burner or to both burners, or to all three burners simultaneously.

A further object of the invention is to provide an obstruction between the burner cap and the said disk located at the valve opening in the disk, the said obstruction serving to spread the vapor uniformly under the burner cap openings, instead of flowing directly through the adjacent burner cap openings, whereby the vapor flows evenly through all burner cap openings.

Other objects of the invention will appear from the following description of the construction and operation of the burner and its several parts.

In the drawings:

Figure 1 is a top plan view showing an arrangement of the improvements, the frame

of the stove and oven being indicated in dotted lines.

Figure 2 is an enlarged horizontal sectional view on the line 2—2 of Figure 1.

Figure 3 is a vertical sectional view through Figure 2 on the dotted line 3—3.

Figure 4 is a central horizontal sectional view taken on the line 4—4 of Figure 1.

Figure 5 is an enlarged top plan view of the main burner with its disk removed, the conduit extending to the oven burner being shown partly in horizontal section.

Figure 6 is an inverted plan view of the burner as shown in Figure 1.

Figure 7 is a sectional view of a part of the oven burner taken on the line 7—7.

No claim is made for several parts of the invention as they are very much like the construction shown in the co-pending application of Louis Stockstrom, Serial No. 34,355, filed June the 2nd, 1925, for improvements in hydrocarbon stoves and burners therefor, the said application being assigned to the American Stove Company, the assignee of the present application. It therefore will be unnecessary to describe in detail those parts that are shown in the said application.

In carrying out the present improvement I utilize a main burner housing 1 having projecting horizontally from the rear side 85 the combined vapor and air receiving device 2. The housing 1 has a transversely arranged channel 3 in which a generator tube 4 of the type described in the aforesaid application is located. Below this generator is a 90 torch holding device 5 for receiving a torch (not shown) for initially heating the generator tube 4. All of the foregoing members are constructed like that shown in the above referred to application except in some parts 95 that will be described hereinafter.

One of the features of the present invention is to provide an oven burner 6 that communicates through a conduit 7 with the lower part of the housing 1. Furthermore 100 a burner 8 as here shown is located in rear of the main burner 1 and this burner 8 communicates with the opposite side of the lower part of the main burner through a suitable conduit 9.

As shown the main burner is provided with a division plate 10 that forms the top for the housing of the burner. This divi-

sion plate therefore, forms a large chamber 11 into which the vapor generated by the generator tube 4 flows and from this chamber 11 vapor flows into the conduits 7 and 9 and to the oven burner 6 and to the rear burner 8. A very shallow chamber 12 is located between the burner cap 13 and the division plate or top 10. For the purpose of controlling the amount of vapor that may flow from the chamber 11 into the chamber 12 and thence through the openings in the burner cap 13, this division plate is provided with an opening 14, the said opening being controlled by a suitable valve 15. This valve reciprocates vertically and therefore moves upward to close or partly close the opening 14 or moves downward for the purpose of wholly opening or partly opening the communication with the shallow chamber 12. For the purpose of providing a convenient manner of operating the valve 15, I provide it with a depending stem 16 that passes downward through a suitable sleeve 17 and to a point below the bottom of the chamber 12. An oscillating shaft 18 is journaled in the ends of a U-shaped bracket 19. Located on the inner end 20 of a shaft 18 are an eccentric pin 21 and a cam 22 that engage a lateral U-shaped member 23. These members operate to move the stem 17 up and down and therefore to move the valve 15 correspondingly.

For the purpose of heating the generator tube, the top of the transverse channel 3 is provided with a plurality of transverse slits 24 through which vapor passes downward from the shallow chamber 12 where air is combined with it to supply combustion for heating the said generator tube.

For the purpose of controlling the flow of vapor to the burners 6 and 9, I provide valves 25 that are moved in and out in respect to the inlet end of the conduits 7 and 9. These valves are attached to the inner ends of U-shaped members 26, one of the legs of the U being provided with a line of perforations 27 that engage with a suitably shaped gear wheel 28. Attached to each of these gear wheels 28 are rods 29 carrying at their outer ends suitable handles for rotating the parts. It will be observed that by turning the handles 30 the valves 25 can be caused to move to either closed or open position, for controlling the flow of vapor from the chamber 11 through the conduits and to the respective burners 6 and 9.

From the foregoing description it will be understood that the burner is started by means of a suitable torch (not shown) that is saturated with gasoline and is lighted and placed in the holder 5, the flame from the gasoline passing upward and striking the generator tube 4. After the tube has become heated, then by turning the valve 31, the vapor will flow through the passage 2 as

described in the above referred to application, and fills the large chamber 11 of the housing 1. If it is desired that the main burner should be operative, then the valve 15 is open to the proper extent to permit the vapor to flow from the chamber 11 into the chamber 12 and thence through the slits 32 of the burner cap 13. Likewise the flow of vapor can be controlled to the burners 6 and 9 as previously stated. If it is desired to burn either the burner 6 or the rear smaller burner 8 without operating the main burner, then the valve 15 is moved upward and the opening 14 closed which will shut off the flow of vapor to the main burner and extinguish it. At the same time, however, vapor flows from the large chamber 11 through the passages 13 and downward into the transverse passage 13 where air mixes with it, causing it to burn and to continue to heat the generator. This burning flame is operative all the time that the generator is furnishing vapor, and that is true whether the main burner is operating or not.

The broad principle therefore, of operation of this improved burner is to provide a plate that divides the housing into a distributing chamber 11 and a separate chamber 12, the chamber 12 serving to supply vapor to the main burner and the chamber 11 serving to supply vapor to the side burners. This division plate is so constructed that when the valve 15 is closed, then the chamber 12 thereabove is wholly closed to any communication whatever with the chamber 11 and at the same time vapor is fed to the passages 24 made in the top of the transverse channel 3 for providing a continuous flame for continuously heating the generator tube.

I find it highly desirable to provide some means located between the opening 14 and the burner cap to cause the vapor to flow through the burner cap to spread laterally and fill the whole shallow chamber 12 and thereby supply vapor to all of the burner slits 32 of the main burner. Without some provision for causing the vapor to spread, there would be a tendency to have a heavy flow of vapor through these slits located nearest the opening 14, whereas it is highly desirable to have all of the slits provided with substantially a uniform flow of the vapor.

Therefore in the form here shown, I have provided an obstruction which consists of a plate 33 that is located between the adjacent main burner slits that serves to spread the vapor in the chamber 12.

Preferably the burner caps of the main burner and the burner 8 are arranged to provide parallel series of passages, that are formed in upwardly extending projections 34.

The special construction of the oven burner

6 consists in providing this burner with its two sides 35 and its ends 36 each having their bottoms slit as shown at 37 in Figures 6 and 7. The ends of the parallel parts 35 communicate with a manifold 38 whereby vapor is fed from the conduit 7 into one end of the manifold which conveys it to the burner, the flame burning from the bottom and naturally spreading at each side of the parts 35 and 36 and flows upward to heat the oven.

For the purpose of facilitating the lighting of the burners, I provide means for conveying the fire from the respective burners for the purpose of lighting any desired one of the three.

A suitable lighter 39 is located between the burner 8 and the main burner 1 and a lighter 40 is located between the main burner 20 and the oven burner 6. The lighter 39 consists of a tube 41 that has its outer end 43 communicating with the burner 8, the said tube having its upper portion provided with a longitudinal slit 44 and a surrounding 25 larger tube 45. Hence when the vapor flows into the tube 41, it will catch from the top of the main burner and the fire will flash backward to the vapor flowing through the slits 34 of the burner 8 and lighting it. The larger tube 45 is merely as a protection for the flame therein, and the tube 41 is attached eccentrically to the tube 45.

The lighter between the main burner and the oven burner 6 consists of the said outer tube or trough portion 40 and an inner tube 46 that has a series of transverse slits 47 extending throughout its length. Centrally this lighter 40 communicates with the conduit 7 as shown by dotted lines 48. Hence 40 when the valve 25 is open for the flow of vapor to the oven burner 6, vapor will flow to the inner tube 46, through the slits 47 lighting at the generator and then flashing backward and lighting the oven burner.

45 It will be understood that when the generator is working and the main burner not lighted, then the main burner can be lighted by opening the valve 14 causing then the vapor to flow through the slits 32 when it will be lighted from the inner end of the lighter 39. When the generator is working, one burner can be lighted from another burner.

In Figure 1 I show in dotted lines 49 the outline of a stove and by dotted lines 50, the outline of an oven in which the oven burner 6 is located. The member at the left of the oven is usually termed the open burner frame. I desire it understood that the burners may be arranged in any suitable relation to the main burner. That is to say the burners in the open part of the stove may be arranged as in ordinary gas stoves, and the communication 7 may be made to the center of the oven burner. In view of this, various changes will present themselves to

those skilled in the art without departing from the spirit and scope of a fair interpretation of the appended claims.

Having thus described my invention, what I desire to claim and secure by Letters Patent is:

1. A hydrocarbon burner comprising a main burner housing, a division plate located adjacent its upper end dividing the said housing into a lower large and an upper 75 small chamber, the said housing having a transverse channel way, a generator located in the channel way, the top of the channel way having burner passages, a burner cap located above the division plate, and the division plate provided with a valve controlled opening for controlling the flow of vapor from the lower to the upper chamber.

2. A hydrocarbon burner comprising a housing, a division plate dividing it into upper and lower chambers, an auxiliary burner communicating by a conduit with the lower chamber, and a valve controlling the said conduit comprising a U-shaped member having perforations and carrying at its inner end a valve, and a wheel engaging one leg of the U-shaped member for the purpose of moving it back and forth.

3. A hydrocarbon burner comprising a housing having a division plate supported at its upper end, thereby constituting substantially the whole housing into a lower vapor chamber, a horizontal main burner plate supported above the said division plate, the division plate having a single opening establishing communication between the said chamber and the burner, an oven burner, a vapor conduit between the oven burner and the said large chamber of the main burner, a vertically movable horizontal valve located below 105 said division plate and adapted to close the said division plate opening, and a generator passing through the said main burner for supplying vapor for the purpose described.

4. A hydrocarbon stove comprising an oven and an open burner portion, a main burner in said open burner portion comprising a housing, a division plate located at the upper part of the housing, thereby dividing it substantially into a lower chamber substantially coextensive with the housing, a horizontal main burner plate located above the division plate, the division plate having a single opening establishing communication between said chamber and the burner plate, a large oven burner located within the oven, a conduit between the said large burner and the large chamber of the main burner, a vertically movable horizontal valve adapted to close the said opening, and a generator passing through said main burner chamber and receiving vapor therefrom, whereby the said main burner may be cut off or turned on without affecting the flow or passage of vapor to the said large oven burner.

5. A main burner housing having a centralized air passageway passing vertically therethrough, a horizontal division plate located substantially at the upper end of the housing dividing its lower portion into a chamber substantially coextensive with the said housing, the division plate having a single passageway located therein at one side of the said vertical air passageway, an auxiliary burner having communication with the said chamber, and a valve located below the said division plate and adapted to control the said opening therein, the parts operating substantially as described.

15 6. A hydrocarbon burner comprising a housing, a horizontal division plate located substantially at the top of the housing thereby forming its lower portion into a chamber substantially coextensive with the housing, a main burner cap located above the said division plate, said division plate having a single opening located therein, a valve controlling the said opening, and a spreader located adjacent the fuel passages in the said burner cap for permitting only a small part of the vapor to pass it and causing the major portion thereof to spread under the burner cap for the purpose described.

7. A hydrocarbon burner comprising a housing having a horizontal division plate in its upper portion, thereby dividing it into a lower large vapor chamber, said division plate having a single opening, a valve controlling the said opening, a burner plate located above said division plate having upwardly extending elongated hollow portions with a plurality of transverse burner slits, and a spreader located at the bottom of said hollow portion substantially closing it against the passage of vapor, thereby causing the larger portion of the vapor to spread under the cap to the remaining burner slits.

8. A hydrocarbon burner comprising a housing having in its upper portion a horizontal division plate dividing it into a large lower vapor chamber, a burner cap located above the division plate having a plurality of elongated parallel upwardly extending hollow portions provided with transverse burner slits, the said division plate provided with a single opening located substantially under one of the said upwardly extending hollow portions of the burner cap, a valve controlling the said opening in the division plate and a spreader located under one of the said upwardly extending hollow portions and permitting only a part of the vapor to flow to it, thereby causing the major por-

tion of the vapor to spread and flow to the remaining upwardly extending hollow portions.

9. A hydrocarbon burner comprising a housing having located in its upper portion a horizontal division plate dividing it into a lower large vapor chamber, a burner cap located above the division plate, said division plate having a single opening, a valve adapted to control the said opening, an auxiliary burner, a conduit connecting the said auxiliary burner with the lower chamber, a valve controlling the said conduit and a movable member connected with the valve substantially U-shaped, and means engaging one of the arms of said member whereby it is moved back and forth for the purpose described.

10. A hydrocarbon range having an open burner portion and an adjacent oven portion, a main burner housing located in the open burner portion, said housing having a division plate located substantially in its upper portion, thereby dividing it into a large lower vapor chamber, a main burner cap located above the division plate, the division plate having a valve controlled opening establishing communication between the said chamber and the burner cap, an oven burner located in the oven and a conduit passing through the wall adjacent the said open portion, the conduit connected with the said large chamber of the main burner, a valve controlling the said conduit communication, and a generator for the main burner, whereby the said burners may be operated in the manner specified.

11. A hydrocarbon burner comprising a shallow horizontal housing having adjacent the top a division plate forming substantially the whole housing into a large lower vapor chamber, a horizontal burner cap supported above the said division plate, thereby constituting a main burner chamber thereabove, the division plate having a single opening establishing communication between said vapor chamber and the main burner chamber, and a vertically movable horizontal valve enclosed within the housing and adapted to open and close the said single opening in the division plate, means extending externally to the housing for controlling the said valve whereby the operation of the main burner can be controlled through the said valve.

In testimony whereof I hereunto affix my signature.

FREDERICK L. FULDAUER.
